UNITED STATES PATENT OFFICE.

HERBERT HASTINGS, OF ROCHESTER, NEW YORK, ASSIGNOR TO GERMAN AMERICAN
BUTTON COMPANY, OF ROCHESTER, NEW YORK, A CORPORATION OF NEW YORK.

ASSORTING-MACHINE.

1,082,632.

Specification of Letters Patent. Patented Dec. 30, 1913.

Application filed April 8, 1912. Serial No. 689,256.

To all whom it may concern:

Be it known that I, HERBERT HASTINGS, of Rochester, in the county of Monroe and State of New York, have invented certain new and useful Improvements in Assorting-Machines; and I do hereby declare the following to be a full, clear, and exact description of the same, reference being had to the accompanying drawings, forming a part of this specification, and to the reference-numerals marked thereon.

My present invention relates to machines employed for assorting or grading articles and distributing them according to their size, and it has for its object to provide an apparatus of this character comprising generally a hopper into which the articles are placed, a continuously moving member therein, gripping devices coöperating therewith for the purpose of engaging articles and holding them while being transported and means for actuating said gripping devices, which are moved to release the articles held by them at different points along the path through which the articles are carried, to the end that objects of one size may be deposited at one place and those of another size may be dropped at another place.

To these and other ends the invention consists in certain improvements and combinations of parts, all as will be hereinafter more fully described, the novel features being pointed out in the claims at the end of the specification.

In the drawings: Figure 1 is a side elevation of a machine constructed in accordance with my invention illustrating one embodiment thereof; Fig. 2 is a top plan view; Fig. 3 is an enlarged plan view illustrating the releasing operation of the grippers; Fig. 4 is a cross-sectional view taken on the line 4^x—4^x of Fig. 2; Fig. 5 is a similar view taken on the line 5^x—5^x of Fig. 3; Fig. 6 is a detail view illustrating the operation of the wipers, taken on the line 6^x—6^x of Fig. 2; Fig. 7 is a detail view of the brush, parts of this mechanism being shown in section, taken on the line 7^x—7^x of Fig. 2; Fig. 8 is a detail sectional view taken on the line 8^x—8^x of Fig. 7; Fig. 9 is a detail view illustrating the spring gates of the receiving chutes, showing the parts as they appear

along a sectional line indicated by 9^x—9^x in Fig. 3. 55

Similar reference numerals throughout the several figures indicate the same parts.

In illustrating the present embodiment of my invention I have shown an assorting machine comprising a semicylindrical hopper wall 1, the bottom 2 of which comprises the revoluble disk, journaled upon a central shaft 3 carried in a bearing on the underlying frame 4 of the machine and provided with a worm gear wheel 5 driven by a worm 6 on the driving shaft 6 which is rotated continuously by any suitable source of power. The bottom of the hopper is inclined and consists of a circular plate or disk 2, the edge of which is chamfered as indicated by 7, and provided with notches 8, which are preferably spaced equidistantly, having curved bottom and parallel side walls, as shown, which latter are at a slight angle to the radii of the disk so that, with reference to the direction of rotation of the disk, the outer portions or mouths of the notches are in advance of their bottom edges. 75

Surrounding the disk 2, and spaced therefrom, is an annular ring 9, which is attached 80 to the disk by a plurality of arms 10. A convenient way to construct these parts is to cast the disk 2 and the ring 9 as an integral structure, and to provide these parts respectively with flanges or rims 11 and 12, 85 which are connected at various points by the ribs 10. The ring 9 is preferably arranged below the plane of the disk 2 and the notches 8 on the periphery of the latter are formed in a detachable ring, or ring sections 13, thus more conveniently providing for their interchangeability. 90

Extending upwardly from the ring 9 are pairs of bosses 14 and 15 in which in alignment with each of the notches 8, are guided 95 the article gripping devices. In the present instance each of the latter comprises a presser plate or head 16 having a slightly curved outer face, carried at the extremity of a tube 17 which is impelled forwardly in a direction toward the bottom of its corresponding notch 8 by a spring 18. The movement of the tube is limited by a pin or screw 19 arranged in the boss 15 and lying in an elongated slot provided in 100 the walls of the tube. The gripping mem- 105

bers are moved outwardly against the action of the springs 18 by a plurality of cam surfaces A, B and C, which coöperate with the rollers 20 carried on the outer ends of the tubes 17.

The ring 9 and the gripping devices carried thereon are housed within the frame of the machine, as shown particularly in Figs. 4 and 5, comprising the annular underlying bottom member 25 attached to the part 4, and the overlying ring 26. The latter part is provided with a lip or flange 27, which extends downwardly and inwardly beneath the notched peripheral portion of the disk 2 for the greater portion of its circumference. This flange or lip commences at the point 27^a and terminates at the point 27^b, and both of its ends are considerably above the horizontal diameter of the disk, so that any articles placed in the hopper 1, which are of suitable size, may be received in the notches 8 and by them carried along in the direction of rotation of the disk. The intervening space between the ends 27^a and 27^b of the flange 27 is for the most part occupied by a plurality of discharge chutes A', B', C', etc., arranged with their upper ends in a curved row beneath the notches in the upper edge of the disk, and in such a position relatively to the cam surfaces A, B and C that they may respectively receive the articles held in said notches by the gripping devices when the latter are actuated by said cams sufficiently to release the articles when they are in alinement above one another of said chutes.

In explaining the operation of the machine, it should be remarked that the cams A, B and C, etc., are cut on the face of a ring 28, which is supported on the part 25 of the frame. The major portion of this cam ring comprises the surface 29 which retracts each of the gripping devices to the limit of its outward movement, holding it in this position during its rotation beneath the hopper until it arrives at the point where the articles received in the recesses 8, during their rotation underneath the mass of the articles in the hopper, are about to pass off the end 27^b of the supporting flange 27. Here the surface 29 is cut away, as indicated at 30, to meet the cam surface A². The size of the articles contained in the recesses determines the inward movement of each presser head 16. The latter compressing the article against the bottom of the recess, will hold it securely and permit it to be transported until the article reaches one or another of the discharge chutes. If the article is small, then the roller 20 will engage the cam surface A, when it will be deposited into the chute A'; on the other hand if the article is of larger size, the gripper will not be tripped until one of the succeeding cam surfaces, such as C, engages therewith and per-

mits the article to drop into the chute C'. Each of the cam surfaces, it will be noticed, is concentric to the center of movement of the gripping devices, but each of said surfaces is arranged at a slightly increased distance from said center, and as there are several of these surfaces and an equal number of discharge chutes, each of which leads to a separate receptacle, a very accurate grading of the articles to be handled may be obtained.

In Fig. 9 the upper ends of several of the discharge chutes are illustrated, and the division walls between these are shown as provided at their upper ends, with spring gates 31 which will yield to prevent breakage of the parts and accommodate an article which may in some way occasionally become caught between them and one of the arms 10.

The articles, it will be understood, are deposited *en masse* in the hopper 1, and in the handling and assorting of some kinds of articles, such as the vegetable ivory nuts used in the manufacture of buttons, it is desirable to assort them according to length; therefore, when the machine is employed for such a purpose, I preferably employ in conjunction with the notched disk a rotary brush and a wiper, which will serve to position the nuts lengthwise in the notches 8 in the disk. The rotary brush may comprise a head 32 having flexible blades 33 the edges of which may be curved as shown in Fig. 4. The head 32 is carried upon the shaft 34 provided with the pulley 35 rotated by the belt 36 driven from the shaft 6. This shaft is preferably carried in the frame piece 37 pivoted at 38 and movable toward and from the disk by the adjustment of a thumb nut 39 on a bolt 40. The wiper employed in connection with the brush is arranged in rear of the latter as indicated by 41, Figs. 2 and 6. It is supported on a pivot 42 on an overhanging arm 43 secured to the ring 26 and is operated in one direction by a spring 44, so as to normally stand in a position above the path of the recesses 8, so that any of the nuts which are not turned or rotated into an endwise position in their respective recesses will be so adjusted upon further engagement with the wiper, as shown in Fig. 6. The coöperative action of the brush and wiper is such that any nuts which do not adjust themselves into proper position in the recesses will be rolled over and turned around before leaving the support 27 so as to lie lengthwise in the slots. This adjustment of the articles occurs near the end 27^b of the support just in advance of the point where the gripping devices are allowed to close against the articles.

In carrying out my invention, it will be observed that the articles are held by engaging their opposite ends between relatively stationary and movable surfaces

which travel continuously, the former being the bottom of the recesses or pockets 8 and the latter the presser heads 16. The fingers or projections between the recesses 5 do not assist in supporting the articles after they have been gripped, but merely aid in arranging elongated articles, such as vegetable ivory nuts, in lengthwise position so that the grippers may act as gages to measure 10 the length or greatest dimensions of each article. These fingers also act as a means for advancing the articles along the support and positioning them with their longitudinal axes in alinement with the 15 grippers or gages.

I claim as my invention:—

1. In an assorting machine, a receptacle for the articles to be assorted, means for arranging said articles in a predetermined 20 position relatively to their lengths, means for independently gaging and holding the articles lengthwise and while held transporting them and means for releasing said articles at different points in their path of 25 movement to separate them into classes with respect to their length.
2. In an assorting machine, the combination with a receptacle for articles and a movable conveyer comprising a plurality of 30 articles engaging devices each adapted to engage and transport a single article and comprising a movable member, of means arranged in the path of movement of said members for operating them to release the 35 articles carried thereby.

3. In an assorting machine, the combination with an article container and a movable conveyer adapted to receive articles therefrom, comprising an abutment and a clamping member movable relatively thereto, the position of which is determined by the size 40 of an article engaged between it and the abutment, of means adapted to coöperate with said member to operate it to release the article at one point or another in its travel depending upon the distance the movable member is separated from its abutment.

4. In an assorting machine, the combination with an article container and a movable 45 conveyer comprising a relatively stationary surface and a plurality of spaced movable clamping members, said conveyer being adapted to receive articles from the container disposed endwise between said surface and each of its clamping members, of means for tripping the several movable members independently of each other and at different points in their movement to release the articles held by them at various 50 points in their travel according to their lengths.

5. In an assorting machine, the combination with a movable conveyer having recesses and gripping devices arranged to engage 55 articles placed in the recesses, of means

for holding said gripping devices in inoperative position, releasing them and subsequently retracting them at successive points in the movement of the conveyer, the retracting movement of the grippers being determined by the position of the gripping devices by reason of the size of the article engaged thereby. 70

6. In an assorting machine, the combination with a support and a conveyer movable thereover having recesses, of movable gripping devices adapted to engage articles in each of the recesses and to carry them when the conveyer moves beyond the support and means for successively tripping the gripping devices to release the articles, said means operating to cause articles of different sizes to be deposited at different points in the travel of the conveyer. 75

7. In an assorting machine, the combination with a hopper and a conveyer having a plurality of recesses moving continuously therethrough, of a movable gripping device for each of said recesses adapted to engage articles received therein, means for holding the gripping devices retracted during a portion of the movement of the conveyer, said means being adapted to release the grippers to engage articles deposited in their respective recesses and also subsequently retract said gripping devices to cause articles of various sizes to be released at different points in the travel of the conveyer. 90

8. In an assorting machine, the combination with a support, a movable member traveling continuously thereover and having recesses and a gripping device arranged in alinement with each of said recesses and adapted to clamp articles placed therein and to carry them when the recesses move beyond the support, of a cam track for holding the gripping devices retracted, adapted to release the latter to engage the articles and also provided with successive step portions for retracting the gripping devices at different points in the movement of the conveyer to effect the release of the articles carried thereby at different points in the travel of the conveyer according to the size of said articles. 100

9. In an assorting machine, the combination with a hopper having a bottom provided with an opening therein, a rotary conveying member having peripheral recesses adapted to receive articles placed in the hopper, of gripping devices adapted to engage said articles and transport them over the opening in the bottom of the hopper, and tripping devices engaged by the gripping devices at different points in their travel according to the size of the articles carried in the recesses to release and deposit said articles according to their size. 115

10. In an assorting machine, the combination with a revolute disk provided with 130

recesses in its periphery, a ring surrounding the disk and separated therefrom and gripping devices carried on the ring and movable lengthwise of the pockets, of a cam 5 for retracting the gripping devices successively during a given portion of their travel.

11. In an assorting machine, the combination with a disk having a notched periphery, a support spaced therefrom and movable 10 with the disk, and gripping devices arranged one for each of the notches in the disk, each gripping device being adapted to engage articles received in the notches while carried along said support, a circular cam track re- 15 tracting said grippers during a portion of their movement, provided with a depression permitting the grippers to move relatively toward their respective notches and also hav- 20 ing a series of cam steps adapted to retract said grippers successively during another portion of their movement.

12. In an assorting machine, the combination with a hopper, a rotatable inclined disk located in the bottom of the hopper having 25 recesses in its periphery, a support under- lying said recesses at the lower portion of the disk and a plurality of discharge chutes, for receiving articles of different sizes, underly- 30 ing said recesses at the upper edge of the disk, of a gripping device movable longitudinally of each of said recesses and adapted to engage an article therein, means for holding said gripping devices retracted and releasing them while the recesses are 35 traversing a portion of the support, and means located relatively to each of said chutes adapted to engage said gripping de- 40 vices to trip them when the article held thereby is over one or another of the dis- charge chutes and is of the size to be re- ceived by said chute.

13. In an assorting machine, the combination with a hopper, an inclined disk therein forming the bottom of the hopper and pro- 45 vided with recesses in its periphery, a ring 45 surrounding the disk and supported thereon and gripping devices carried on the ring and co-operating with the several recesses, of a framework inclosing the ring having a seg- 50 mental portion forming a support under- lying the recesses at the lower side of the disk, a plurality of discharge chutes ar- ranged beneath the recesses in the upper side of the disk, a circular cam track re- tracting the gripping devices while the re- 55 cesses are traversing a portion of said sup- port and permitting them to engage articles therein and transport them to a position above one or another of said chute, said ring being also provided with a plurality of 60 stepped shoulders for retracting said grip- ping devices.

14. In an assorting machine, the combination with a frame, a circular member jour- 65 naled thereon having an unsupported edge 65 provided with recesses, a ring moving with the circular member and spaced from the edge thereof and grippers carried on the ring, of a cover plate on the frame inclosing 70 said ring having a central aperture exposing the circular member, an arcuate flange car- 75 ried on the cover and underlying a portion of said unsupported edge and means for re- tracting the grippers successively at differ- ent points during their movement across the space intervening between the ends of the flange.

HERBERT HASTINGS.
